UNITED STATES PATENT OFFICE.

GEORGE W. PRICE, OF BALTIMORE, MARYLAND, ASSIGNOR OF ONE-THIRD
TO JOSEPH R. FOARD, OF SAME PLACE.

DEVICE FOR LOADING AND UNLOADING VESSELS.

SPECIFICATION forming part of Letters Patent No. 367,061, dated July 26, 1887.

Application filed March 10, 1887. Serial No. 230,341. (No model.)

To all whom it may concern:

Be it known that I, GEORGE W. PRICE, of the city of Baltimore and State of Maryland, have invented a new and useful Improvement 5 in Devices for Loading and Unloading Vessels, of which the following is a full description.

In the drawings, Figure 1 shows a portion of the track upon which the carriage travels 10 with the carriage seated thereon, the bucket with its bail, the projections to which the latch is pivoted, the looped trigger for tripping the latch, and the bow-piece attached to the track, against which the trigger comes in 15 contact to lift the latch. Fig. 2 illustrates a side view of the parts shown in Fig. 1, showing also the track in section. Fig. 3 is a view of the track with its end attachments, the bucket hanging thereto, and also in dotted 20 lines the bucket tripped and in the act of dumping its load.

This device is an improvement upon the invention described in a specification heretofore filed on the 16th day of March, 1886, for an 25 "improvement in apparatus for loading and discharging vessels," which said application was allowed on the 3d day of August, 1886; and it consists in the construction and arrangement of the dumping or tripping device, 30 whereby greater certainty is attained in dumping the bucket to discharge its load.

In the drawings, A represents the track along which the carriage is impelled by the rope; B, the carriage and hook; C, the bucket; 35 D, the cars into which the load is dumped from the bucket. The track may be constructed with a flange, as shown at a', and upon this flange I have placed the bow-shaped piece a''. This piece may be made of any suitable material, having its ends formed to clasp the flange a', as shown at a'', and is secured in its place by the set-screw a''. Any other means for clamping the bow may be used, as the object is to make it adjustable. In order 40 to secure lightness, I prefer to construct the bow of thin iron or other metal and pivot at or near its middle the latch or thumb-button a''. The construction of this button is such that it may be turned up in contact with the 45 bottom of the track to stiffen the bow. It also serves the additional purpose of fixing the

bow in place on the track when adjusted, and when used in this way the set-screw a'' may be dispensed with.

It will be observed that the bucket when 55 propelled runs sidewise, so as to discharge its load by tipping in a direction crosswise of the track. The object of this is to enable the bucket to dump into the cars D in the direction of their length. The track upon which 60 these cars run is usually placed upon the wharf, so that the cars will run under the bridge or track A. To dump a bucket automatically while running in this way, it is necessary that the latch which holds it in place 65 should be as nearly central as possible, and that the trigger when operated will lift the latch at once and not push it aside. To accomplish this, I attach to the bail F of the bucket the two lugs or projections e e', Fig. 1, 70 and arrange them to stand backward and upward. The trigger E is then pivoted between these lugs by the pin e'. By this arrangement the trigger is in a position nearly central with the bail and a line drawn lengthwise through 75 the bucket. The loop H is constructed of light metal and formed so as to pass around the hook of the carriage B and the ring at the top of the bail F. The two ends of the loop are riveted or otherwise fastened to the trigger at h.

The operation of the device is as follows: The adjustable bow is placed at any point on the track where the dump is desired. The carriage having the bucket suspended runs 85 along the track impelled by the rope until the upper end of the loop reaches the nearest end of the bow a'', the end of which is in the form of an inclined plane. As the carriage progresses the loop is depressed, and as the trigger is central the lift is straight up and the trigger is released just at the point where the dump is desired. By the arrangement of the loop around the ring and hook these parts are 90 escaped, at the same time leaving plenty of 95 room to avoid the bail as the loop descends.

The bucket is of the class which is tipped by its own load when the trigger is released.

What I claim is—

1. In a loading and discharging apparatus, 100 the track A and the bow-shaped piece a'', made adjustable upon the track, in combination

central pivot joint with the bucket C, bail F, having the projections e', the trigger E, pivoted to the projections e', the loop H, and the bucket-carrier, substantially as described.

5. 2. In a loading and discharging apparatus, the combination of the bucket, the trigger E, pivoted centrally with the bail and bucket,

and the loop H, passing around the bail-ring and carriage-hook and secured at its ends to the trigger E, substantially as described.

GEORGE W. PRICE.
